UNITED STATES PATENT OFFICE.

JOHN C. BOSS, OF ELKHART, INDIANA.

AIR-BOX OF BRICK-KILNS.

1,138,532.

Specification of Letters Patent.

Patented May 4, 1915.

Application filed May 6, 1912. Serial No. 695,435.

To all whom it may concern:

Be it known that I, JOHN C. BOSS, citizen of the United States, residing at Elkhart, Indiana, have invented certain new and 5 useful Improvements in Air-Boxes of Brick-Kilns, of which the following is a specification.

My invention, hereinafter described, relates to the air supplying and distributing 10 boxes of brick kilns, of the class shown in Letters Patent of the United States, granted to me, on the 14th day of May 1901 No. 673,896, and that of October 28, 1902, No. 712,035. In these patents the air boxes are 15 located in the bottom of the fire chamber, and are so arranged that the fuel lies over and about them, and the air forced into the said boxes is distributed upward into the mass of coal, whereby combustion is evenly 20 and effectively maintained. I have, however, found these boxes less effective when the cheaper and more refractory fuels are used, such as hard coal screenings, hard coal culm or the cheaper grades of lignite. As these 25 fuels are more available in some localities and cheaper, I have devised a form of air distributing box, adapted more effectively to consume such fuels. This is a modification 30 of the form shown in the aforesaid patents, though the location thereof, and the general construction and arrangement are the same.

My said invention is illustrated in the accompanying drawings, in which—

Figure 1 is a transverse section of an arch 35 showing my improved air-box as applied thereunder; Fig. 2 is a longitudinal section of the box partly broken away. Fig. 3 is a plan view of the same with the top plate removed, and Fig. 4 is a sectional view showing a modified form of fastening means for 40 the top plate.

In these drawings I have shown a single combustion chamber, such as that shown in my prior patents, and used by me, in which 45 the air box is located preferably in the axial line of the chamber, and in the bottom as indicated at A. It will be understood that the fuel is placed over and on each side of the box, in said patents and the orifices, 50 through which the air is discharged, are arranged in the top of the box, and direct the currents of combustion supporting the

air upward, through the top of the air box, into the fuel above it. But I have found that in the kinds of fuel, above mentioned, 55 this series of direct upward currents works less effectively, and by further experiment have found, that, with these fuels, a lateral current is much more effective. I provide for this effect placed over the box, a plain 60 metal plate B, substantially coterminous with the top of the box, but raised therefrom, so as to permit the air, forced upward through the orifices in the top of the box, to impinge forcibly against the under surface 65 of said plate, and to be thereby directed outward through the narrow space 3, between the top of the box and the under surface of the plate. These narrow horizontal blasts of air strike laterally into the coal, with force, 70 and then rise, through the incumbent body with such effect that I am able, with this apparatus, to burn, as effectively, the cheaper coals, as with my prior boxes, I burned the better and more expensive coals. 75 It will be understood that one of these boxes is thus located in each fire chamber of the kiln and is supplied with air under pressure, from a proper source, through a branch pipe 4. 80

The orifices in the top of the boxes are shown at 5. They are transverse slots, the walls of which flare upward, and spread the streams of air, which impinge upon the plate. In order to hold the plate in proper 85 relation to the top of the box, and removable, I form by casting or otherwise, on the under side of the plate, inclined or curved lugs 7, which engage removably with inclined or curved holes 8, in the top of the 90 box. These are located to hold steadily and symmetrically, the cover on the box. Knobs or ribs 9 also formed on the under side of the plate, regulate the distance between the plate and box top, and find a bearing in 95 the hollows 10. Instead of the curved lug, I may use a bolt, as shown at 11, Fig. 4, the bolt being preferably cast with its head embedded in the top plate, on the under side, in proper relation to the hole in the top of 100 the box. The bolt passes through this top and is held by a nut 12. The lug and corresponding hole are, however, more convenient.

I claim as my invention:—

The combination with a brick kiln arch and its imperforate floor or hearth for supporting fuel, of an air box embedded in said floor and having its top open for the discharge of air and flush with the surface of the floor and a plate covering said top and overlapping said walls of the box and spaced therefrom to form a narrow air exit for dis-

charging air laterally into said fuel at the 10 point where it contacts with said floor.

In testimony whereof, I affix my signature in presence of two witnesses.

JOHN C. BOSS.
